Primary Examiner — Mary Ann Calabrese(74) *Attorney, Agent, or Firm* — Daniel A. Tallitsch; Baker & McKenzie LLP(57) **CLAIM**

The ornamental design for a channel banner for a tray, as shown and described.

DESCRIPTION

FIG. 1 is a first perspective view showing my new design; FIG. 2 is a top elevational view thereof;

FIG. 3 is a bottom elevational view thereof;

FIG. 4 is a front elevational view thereof;

FIG. 5 is a left elevational view thereof;

FIG. 6 is a right elevational view thereof;

FIG. 7 is a back elevational view thereof; and,

FIG. 8 is a second perspective view showing my new design in its intended use.

The broken lines are for illustrative purposes and form no part of the claimed design.
